United States Patent Office

Des. 211,747
Patented July 23, 1968

211,747

PLANTING TOOL

Leonard C. Odell, 4504 W. 44th St.,
Minneapolis, Minn. 55424

Filed Feb. 20, 1967, Ser. No. 5,866

Term of patent 14 years

(Cl. D35—2)

FIG. 1

FIG. 2

FIG. 3

FIG. 4

FIG. 1 is a view in front elevation of a planting tool showing my new design; the rear view being substantially a mirror image of said front;

FIG. 2 is an elevational view thereof as seen from the right side of FIG. 1, the left side being substantially a mirror image of said right side;

FIG. 3 is a view in top plan thereof; and

FIG. 4 is a view in bottom plan thereof.

I claim:

The ornamental design for a planting tool, as shown and described.
